UNITED STATES PATENT OFFICE.

JOSEPH BERGSTEN, OF ROCKFORD, ILLINOIS.

TOWEL-RACK.

SPECIFICATION forming part of Letters Patent No. 320,211, dated June 16, 1885.

Application filed January 6, 1885. (Model.)

To all whom it may concern:

Be it known that I, JOSEPH BERGSTEN, of Rockford, in the county of Winnebago and State of Illinois, have invented a new and 5 Improved Towel-Rack, of which the following is a full, clear, and exact description.

The object of my invention is to provide a simple, inexpensive, convenient, and efficient rack for holding towels.

10 The invention consists in a towel-rack made with a fixed and an adjustable roller supported parallel with each other in end brackets, springs being provided to hold the rollers toward each other to clamp the towels between them.

15 Cams are arranged on one roller to act on the other roller to separate them for placing the towels in the rack, all as hereinafter fully described and claimed.

20 Reference is to be had to the accompanying drawings, forming part of this specification, in which similar letters of reference indicate corresponding parts in all the figures.

Figure 1 is a perspective view of my improved towel-rack with a towel held thereby. Fig. 2 is an end elevation of the rack, partly in section, and with the rollers in position for holding the towels, and Fig. 3 is an end elevation of the rack with the inner or 30 clamping roller thrown back for placing towels in the rack.

The letters A A indicate the opposite end brackets of the towel-rack, which are made alike and preferably of cast metal, and with 35 holes through which screws or nails may be passed for fastening them to a partition, wall, or other support.

Each bracket A has a bearing, a, in which the reduced end b of the outer towel-holding roller, B, is journaled, and a cam or eccentric plate, C, is hung on each end b of roller B, between its end shoulders and the brackets A, said cams having finger-pieces c, for convenience in operating them.

45 At D is shown the inner or towel-clamping roller, which is supported by its reduced ends d in slots E, formed in the brackets A. Behind the slots E, in line with and opening into them, are formed recesses F, making 50 bearings or supports in which presser-pins G

slide. Springs H are placed around the pins, between the back ends of the slots E and the heads g of the presser-pins, to force the heads against the bearings d of roller D, and hold said roller toward or in contact with the front 55 roller, B, as seen in Fig. 2.

To place one or more towels, I, in the rack, one or both of the cams C C will be turned by pressing down on their finger-pieces c, which carries the eccentric faces of the cams 60 against the roller D to force it back against the tension of the springs H, as in Fig. 3, when one corner or end of the towel may be passed between the rollers B D, from the top, preferably, and when the cams are turned 65 back again, as in Figs. 1 and 2, the springs H will force the roller D outward, and the towel or towels will be held firmly between the rollers.

Should one or more towels be in the rack, 70 and it is desired to hang another towel therefrom, a cam, C, at one end of the rack only need be turned to separate the rollers at that end to allow the extra towel to be placed between the rollers without dropping those already in the rack.

To remove the towels, it only is necessary to pull them from between the rollers, which turn as the towels are drawn out, thus preventing damage to the towels, as will readily 80 be understood.

I am aware that a towel-rack composed of two rollers journaled in a bracket, one of the said rollers being pressed toward the other roller by a spring, is old and I therefore do not 85 claim such invention.

Having thus described my invention, what I claim as new, and desire to secure by Letters Patent, is—

1. A towel-rack comprising a fixed roller 90 and an adjustable roller, both supported in end brackets, springs tending to hold the rollers in contact, and cams hung on one of the rollers and acting when turned to separate the rollers, substantially as herein set 95 forth.

2. The combination, in a towel-rack, of the brackets A A, roller B, journaled in bracket-bearings a, a roller, D, journaled in the bracket-slots E, presser-pins G, springs H, 100

and the cams C C, mounted on the roller B, substantially as herein set forth.

3. The combination, in a towel-rack, with the brackets A, provided each with a slot, 5 E, and a recess, F, of roller B, journaled in the outer ends of said brackets, the roller D, journaled in the slots E, the pins G, the

springs H, and the cams C on the roller B, as set forth.

JOSEPH BERGSTEN.
